SHOE PLATE FOR A RINK ROLLER SKATE

John S. Coldwell, Milwaukee, Wis., assignor to
 Globe-Union Inc., Milwaukee, Wis., a corpora-
 tion of Delaware

Application August 20, 1949, Serial No. 4,624

Term of patent 7 years

(Cl. D34—14)

To all whom it may concern:

Be it known that I, John S. Coldwell, a citizen of the United States, residing at Milwaukee, in the county of Milwaukee and State of Wisconsin, have invented a new, original, and ornamental Design for a Shoe Plate for a Rink Roller Skate, of which the following is a specification, reference being had to the accompanying drawing, forming part thereof, and in which:

Fig. 1 is a bottom view of a shoe plate for a rink roller skate embodying my new design;

Fig. 2 is a view in side elevation of such shoe plate;

Fig. 3 is a view in rear elevation of such shoe plate; and

Fig. 4 is a view in front elevation of such shoe plate.

I claim:

The ornamental design for a shoe plate for a rink roller skate, substantially as shown.

JOHN S. COLDWELL.
